(57) **CLAIM**

The ornamental design for a cornucopia shaped self help aid, as shown.

DESCRIPTION

FIG. 1 is a front left isometric view of a cornucopia shaped self help aid showing my new design;

FIG. 2 is a front view thereof;

FIG. 3 is a top view thereof;

FIG. 4 is a bottom view thereof;

FIG. 5 is a right side view thereof;

FIG. 6 is a left side view thereof; and,

FIG. 7 is a back view.

The broken lines shown in the figures depict environment for use with the cornucopia shaped self help aid and form no part of the claimed design.
